UNITED STATES PATENT OFFICE.

WILLIAM G. HUGHES, OF DOWNEY, CALIFORNIA.

CHAIN PIPE WRENCH.

Application filed December 17, 1925. Serial No. 75,971.

My invention consists in the novel construction of the chain and connected parts and in the relation of the chain and connected parts to the pipe when in use whereby the tool is cheap to manufacture and efficient in use.

In the drawings forming a part of this application Fig. 1 is a side elevation, partly broken, showing my wrench positioned on a pipe; Fig. 2 is an enlarged plan of the latch portion of the chain; Fig. 3 is a section on the line 3—3 of Fig. 1; Fig. 4 is a side view of a grip link; Fig. 5 is a side view of a chain link; Figs. 6 and 7 are side views of latch links; and Fig. 8 is a side view of a stop member.

Referring to the drawings, the chain that forms the principal portion of my wrench is composed of links 10 having holes 11 in the ends thereof in which bolts 12 are received that hold the links together to form the chain portion of the wrench. On the edge of each link which contacts with pipe 13 are two lugs 14, which lugs engage the pipe when the wrench is in use. The links at one end are connected to grip links 15 by bolts 16. Links 15 are connected to the slotted head 17^a of lever 17 by bolt 18. The links 10 at the other end are connected to latch links 19 by bolt 20. Links 19 on the edge that contacts with the pipe have two lugs 21 and in the other edge have recesses 22 and 23 in one of which the lock bar is received when the wrench is positioned on a pipe. Links 19 also have handle lugs 25 to which the side members 26 of the handle are riveted. Members 26 are connected by bar 27 which is gripped when the chain is positioned on or taken off a pipe. Connector bars 28 at one end are connected by bolt 29 with the nose 17^b of lever 17. At the other end bars 28 are connected to latch links 31 which have lugs 32 on the edge thereof which contacts with the pipe. Links 31 have holes 33 and 34 in the base thereof. A bolt 35 passes through holes 33 and through holes in the ends of the connector bars thereby hingedly connecting the parts. A lock member comprising side members 36 and handle bar 37 and lock bar 38 and stop bar 39 is connected to links 31 by bolt 40 which passes through holes in side members 36 and through holes 34 of links 31. Stop bar 39 is mounted in members 36 and passes through apertures 41 in links 31. Links 31 are pro-

vided with recesses 42 in which bar 38 is received when the wrench is positioned on a pipe. Links 31 have springs 44 which springs bear upon bar 38 and hold it from accidentally coming out of the recesses in links 19 and 31 when the wrench is positioned on a pipe. Lever 17 has in the outer end a recess 45 in which is received the operating cable, not shown, which recess is closed by a sliding bolt 46 when the wrench is in use to prevent the cable from disengaging from the lever. Bolt 46 slides in a bearing 47. Stop members 48 may be provided to prevent the chain from opening too far when in use.

In the manufacture of the wrench the chain links and latch links and grip links and connector bars are formed preferably by stamping the parts out of heavy sheet 75 or bar steel and the head and nose of lever 17 is slotted correspondingly to alternate with the connector bars and grip links.

In the drawings I have illustrated a wrench adapted for use on two sizes of 80 pipe. When recesses 22 and 42 are in register the wrench fits upon the larger size of pipe. When recesses 23 and 42 are in register, the wrench fits upon a smaller size of pipe. By providing each of the various parts with two lugs on the edges which contact with the pipe when the wrench is in use thereon, all danger of deforming the pipe is avoided. By putting in chain links between the connector bars and the latch 90 links the size of the wrench can be increased. The wrench is used in the well known manner of using chain wrenches on heavy pipe.

It will be seen that what I term grip links, 95 latch links, and connector bars virtually comprise a chain of detachable parts, detachably secured together by the lock bars, and that one end of the chain is secured to the nose of the operating lever and the other 100 to the head of the lever at a point below the plane that passes through the center of the pipe when the wrench is positioned for use and that both of said points of attachment are on the same side of the plane and that 105 when a pull is exerted on the operating lever that end of the chain that is secured to the head is forced against the pipe and becomes the fulcrum, while the nose tightens the chain on the pipe. As the fulcrum point is 110 below the center it can not slip back and the action of the lever on the chain is to cause

all parts thereof to more tightly engage the pipe at all points.

Having described my invention, I claim:

1. A chain pipe-wrench comprising a lever having a slotted head and nose, grip links rockably mounted in said head, said point of mounting being below the center of the pipe when the wrench is positioned for use, a chain composed of links connected at one end to the grip links, latch links connected to the other end of the chain, said latch links having outwardly opening recesses in their outer edges, connector bars mounted in the nose of the lever, said point of mounting being below the point of grip link mounting, latch links connected to the other ends of said connector bars, said last latch links having outwardly opening recesses in their outer edges and being adapted to be received between the latch links connected to the chain and thereby register the recesses of both sets of latch links, and a lock bar rockably mounted on one of said sets of latch links, said bar being adapted to be swung into the recesses in the latch links and lock the links together when the wrench is on a pipe.

2. A chain pipe-wrench comprising a lever having a slotted head and nose; a chain composed of links operatively connected at one end to head of said lever below the center of the pipe when positioned for use, said links each having two lugs on their edges which contact with the pipe; a latch member connected to the other end of said chain; a second latch member acting in coordination with the chain latch member; means to lock said latch members against separation when the wrench is positioned on a pipe; and an operative connection between said last latch member and the nose of said lever, said last connection being below the connection to the head of the chain.

3. A chain pipe-wrench comprising a lever having a slotted head and nose; a chain operatively connected at one end to said head below the center of the pipe when positioned for use; a latch member connected to the other end of said chain; a second

latch member acting in coordination with the first latch member; means to lock said latch member against separation when the wrench is positioned on a pipe; connector bars connected to said second latch member and to the nose of said lever, said last connection being below the connection to the head of the chain, each of said members being provided on their edges which engage the pipe with a pair of spaced lugs.

4. A chain pipe-wrench comprising a lever having slotted head and nose; grip links rockably connected to said head and entering the slots therein, said connection being below the center of the pipe when positioned for use; a chain composed of links operatively connected at one end to said grip links; a latch member operatively connected to the other end of said chain, said latch member having outwardly opening recesses in its outer face; a handle connected to said latch member; a second latch member acting in coordination with the first latch member and having in its outer edges recesses adapted to register with the recesses of the first latch member; a locking bar rockably mounted on said last latch member, said bar being adapted to enter recesses in both latch members when the wrench is positioned on a pipe and thereby prevent the wrench from separation from the pipe; connector bars connected to said second latch member and to the nose of said lever, said links each having on their edges, which contact with the pipe, two spaced lugs.

5. A chain pipe-wrench comprising a lever having a slotted head and nose, a chain composed of sections detachably connected together and having one end connected to the nose and the other end connected to the head, said points of connection being both on one side of the plane that passes through the center of the pipe when the wrench is positioned for use.

In witness that I claim the foregoing I have hereunto subscribed my name this 11th day of December, 1925.

WILLIAM G. HUGHES.
